CLAIM

The ornamental design for an ant moat for nectar bird feeder, as shown and described.

DESCRIPTION

FIG. 1 is an isometric view of an ant moat for nectar bird feeder.

FIG. 2 is a bottom perspective view thereof.

FIG. 3 is a side view thereof.

FIG. 4 is a top view thereof; and,

FIG. 5 is a bottom view thereof.

(Continued)

The broken lines in the Figures show portions of the ant moat for nectar bird feeder that form no part of the claimed design.
